UNITED STATES PATENT OFFICE

2,249,149

AUXILIARY HYDRAULIC DEVICE FOR
PRESSES

Howard F. MacMillin, Mount Gilead, Ohio, assignor to The Hydraulic Press Corporation, Inc., Wilmington, Del., a corporation of Delaware

Original application August 16, 1934, Serial No. 740,148. Divided and this application August 24, 1936, Serial No. 97,579

7 Claims. (Cl. 100—70)

This invention relates to presses, and especially to those having their platens moved by non-hydraulic means.

One object of my invention is to provide a press having a platen moved by any convenient means whether hydraulic or non-hydraulic, and devices for generating fluid pressure operated by the motion of the platen, the fluid pressure thus generated being available for operating various hydraulically-actuated devices and/or providing pressure control.

Another object is to provide a hydromechanical press having its platen moved by whatever means, with an auxiliary hydraulic pressing ram connected to an external hydraulic circuit, with means for releasing the pressure in this circuit and/or reversing the direction of flow of the hydraulic fluid so as to remove the pressure from the auxiliary pressing plunger at the instant the pressure reaches a predetermined amount.

This application is a division of my copending application, Ser. No. 740,148, filed August 16, 1934, now matured into Patent No. 2,128,152.

In the drawings:

Figure 1 is a front elevation, partly in section, showing a press embodying an arrangement for "flash" pressure control, or release of pressure when a predetermined pressure has been reached.

Figure 2 is a front elevation, partly in section, of a press also embodying the "flash" control arrangement, but also including a reversible delivery pump in a closed hydraulic circuit to supply additional fluid to the auxiliary pressing plunger.

Figure 3 is a front elevation, partly in section, of a press also embodying the "flash" control arrangement, but having a variable delivery pump in an open hydraulic circuit wherein the pump discharge is valved to control the direction of movement of the press platen.

Figure 4 is a wiring diagram of an electrical circuit adapted to perform the "flash" control operation for the presses shown in Figures 1 to 3, inclusive.

Press with single-acting generator rams

Referring to the drawings in detail, Figure 1 shows a press having a base 1 joined by side members 2 to the top member 3, as by the strain rods 4, on which are threaded the nuts 5. Mounted on the base 1 is a work table or bed 6. The side members 2 of the press are equipped with guide portions 7 adapted to receive a press platen 8 for longitudinal reciprocation. The keeping of the platen 8 in engagement with the

guide portion 7 is assisted by the retaining plates 9 bolted to the side members 2 of the press.

The press platen 8 may be moved in any convenient manner, such as mechanically or hydraulically. For purposes of illustration, a gear-driven mechanical crank press is shown, but other types may be used without departing from the scope of my invention. In the form of press shown, the platen 8 is provided with a cross shaft 10 journaled in bearings 11 on the upper portion of the platen 8. Pivottally engaging the cross shaft 10 of the platen 8 is a connecting rod 12 having a lower bearing 13, surrounding the cross shaft 10. At its upper end, the connecting rod 12 is provided with an upper bearing 14, which surrounds the crank portion 15 of the main drive shaft 16. The latter is journaled in bearings 17, mounted upon the side members 2 of the press.

The driving end of the main driven shaft 16 is provided with a gear 18 for this purpose. The gear 18 is connected by a clutch mechanism within the clutch housing 19 in such a manner that the gear 18 may be connected or disconnected from the main drive shaft 16, as desired. The clutch mechanism within the clutch housing 19 is actuated by the crank arm 20 mounted on the clutch shaft 21 and connected by the link 22 to the pedal rod 23. The latter is reciprocably supported in the bosses 24 attached to one of the side members 2, and is secured at its lower end by the pivotal connection 25 to the foot pedal 26. By depressing or releasing the foot pedal 26, the gear 18 may be made to operatively engage the main drive shaft 16, or rotate loosely upon it. In this manner, the foot pedal 26 controls the press to provide for its executing working strokes or for its remaining idle, as may be desired.

The gear 18 is driven by a pinion 27, meshing therewith, and mounted upon the countershaft 28 journaled in bearings attached to the side members 2. The opposite end of the countershaft 28 from the pinion 27 bears a flywheel 30 and a pulley 31, whereby the press may be driven, as from an electric motor belted to this pulley. Accordingly, when the pulley 31 is thus rotated, the gear 18 also rotates loosely upon the main drive shaft 16. When the foot pedal 26 is depressed, the gear 18 drivingly engages the main shaft 16 and causes the crank portion 15 thereof to move in an orbital path. This movement causes the connecting rod 12 to move up and down, carrying with it the platen 8. The platen 8 in its lower portion is provided

with a pair of generator cylinder bores 32 and an auxiliary pressing cylinder bore 33. These cylinder bores are connected at their ends by the passages 50 and 51. Reciprocably mounted within the cylinder bores 32 are hydraulic generator rams 46 with heads 47 and having their lower ends secured in sockets 36 in the base 1 (Figure 1). Leakage from the generator cylinders 32 is prevented by the provision of the packings 37, adapted to be compressed by glands 38. Mounted for reciprocation in the auxiliary pressing cylinder bore 33 is the auxiliary pressing ram 45, having an upper enlarged portion 48 and a lower reduced portion 49. Leakage from the cylinder bore 33 is prevented by the packing 43, engaged by the gland 44, which surrounds the reduced portion 49 of the auxiliary pressing ram 45.

In Figure 2 it will be observed that the right-hand cylinder 53 is connected at its upper end by the passage 55 to the space above the enlarged head 48 of the auxiliary hydraulic ram 45, whereas the upper end of the cylinder 52 is connected by the oblique passage 56 to the space below the enlarged head 48. The pistons 57 and 58, however, are provided with hollow longitudinal bores 59, and thus act like telescoping connections, and to some extent like pistons. The bores 59 are connected at their lower ends to the pipes 60 and 61, respectively.

In the arrangement of the present invention, the "flash" type of operation is employed. That is, the pressing pressure is released at the instant it reaches a predetermined value so that substantially no pressure is henceforth exerted upon the work-piece during the remainder of the working stroke. To accomplish this result, an electrical circuit is disclosed below, but it will be understood that mechanical arrangements for accomplishing the same result might also be employed.

The electrical circuit for accomplishing the reversal of the press arrangements shown in Figures 1 to 3, inclusive, is set forth in Figure 4. The principal elements in this circuit are a pressure-operated switch, generally designated 130, a clutch-operating solenoid 131, a clutch-operating contactor switch, generally designated 132, a valve-operating solenoid 133 and a valve-operating contactor switch, generally designated 135. The circuit also contains a double push button starting switch 134, a throw-out switch 129 and an electrical limit switch 136. The mechanical parts operated by the clutch solenoid 131 (Figure 1) consist of a pair of collars 137 on the clutch control rod 23, these being engaged by one end of the solenoid lever 138 which is pivoted at its mid-portion, as at 139, and connected by the connecting rod 140 to the armature 141 of the clutch-operating solenoid 131.

The electrical limit switch 136 serves to place the mechanism out of operation by releasing the clutch through the action of the clutch-operating solenoid 131, and is operated by the collar 142 on the actuating shaft 143. The latter is reciprocably supported in the bearing bosses 144 attached to the machine, and carries an adjustable collar 145 for regulating the position at which the limit switch 136 is actuated. A second adjustable collar 146 serves as a stop to rest against the boss 144 when the actuating shaft 143 is in its downward position. The adjustable collar 145 is engaged by the bored end 147 of the arm 148, the base 149 thereof being secured to the platen, as by the bolts 150. The bored

end 147 loosely surrounds the actuating shaft 143. Consequently, when the platen 8 on its return stroke rises to its maximum position, the end 147 of the arm 148 lifts the collar 145 and the shaft 143, thus causing the collar 142 to throw the limit switch 136 to deenergize the clutch-operating solenoid 131 and to allow the clutch 19 to return to its open position, severing the power connection to the main drive shaft 16.

Each of the press arrangements shown in Figures 1, 2 and 3 employs a double-headed piston valve similar to the piston valve having a valve rod 104 with spaced heads 106 and 107 for distributing the fluid and of reversing its direction. In the present instance, the valve rod 104 is attached to the armature 151 of the valve-operating solenoid 133. When the solenoid 133 is energized, the valve rod 104 is pulled downward so that the piston heads 106 and 107 are in their lower positions. As soon as the solenoid 133 is deenergized, however, the valve rod and its heads move upward under the urge of the coil spring 152.

In the press arrangement shown in Figure 2, the upper end of the valve rod 104 is provided with a clevis 153, which is connected to the bell-crank 154 by the connecting link 155. The bell-crank 154 is pivotally mounted upon the frame bracket 156, and its opposite end is connected to the pump reversal shaft 157 by the link 158. As a result, therefore, the shift of the valve rod 104, through the action of the solenoid 133 or coil spring, simultaneously causes the valve 105 to be shifted and the pump to be reversed.

The press circuit shown in Figure 1 lacks a pump, but is provided with the fluid supply tank 159 and the check valve 160. The latter allows fluid to flow from the tank, but not in the reverse direction.

The press circuit shown in Figure 2 is a closed circuit, the press platen direction being changed by reversing the reversible pump 64. The latter is provided with a differential valve 75 for taking care of insufficient or excess fluid in the circuit.

The circuit of Figure 3 is an open circuit wherein in the pump discharge is valved to control the direction of movement of the press platen. In Figure 3 the valve rod 104 is actuated by the solenoid 133 and the coil spring 152. This pump 114 is a variable delivery pump having a servo-cylinder 115 connected by a pilot line 116 to the main pump line 117, so that the flow control element of the pump 114 is shifted thereby when the pressure in the lines 116 and 117 rises beyond the pressure setting of the servo-cylinder 115, as adjusted by the hand wheel 118. The pressure switch 130 controlling this solenoid 133 also acts as a relief valve, through its port 198 and pipe 199. Hence, the high pressure relief valve 112 in Figure 3 serves merely as an added safety device and may be optionally omitted.

The operation of the electrical circuit for controlling the movements of the presses shown in Figures 1, 2 and 3 is substantially the same for all three arrangements. A single description will, therefore, suffice, after which the slight variations in the hydraulic circuits will be individually described.

To start the press of Figure 1, the starting button 13 (Figure 4) is depressed. The upper bar thereof closes the circuit between the power lines 161 and 162 by way of the operating coil 163 of the clutch-operating contactor switch 132. The latter then becomes energized, attracting its

armature 164 against the urge of the coil spring 165, and closing the respective circuits through its three contactor bars 166, 167 and 168. The contactor bar 166 closes the circuit between the power lines 161 and 162 by way of the limit switch 136, the branch lines 169, 170 and 171, and the push button switch 129. This action maintains the energization of the operating coil 163 of the clutch-operating contactor switch 132 after the starting push button switch 134 has 10 been released.

The closing of the contactor bars 167 and 168 of the contactor switch 132 closes the circuit between the power lines 161 and 162 by way of the windings of the clutch-operating solenoid 15 131. This energizes the solenoid 131, attracts the armature 141 thereof and operates the clutch rod 23 to engage the clutch 19 and start the platen moving downward.

The depressing of the starting push button switch 134, previously mentioned, also causes the lower bar thereof to close the circuit between the power lines 161 and 162 by way of the branch line 172, the operating coil 173 of the valve-operating contactor switch 135, the branch lines 174, 20 170 and 171; and the operating coil 163 of the clutch-operating contactor switch 132. This action shifts the armature 175 of the contactor switch 135, closing its three contactor bars 176, 177 and 178 against the urge of the coil spring 30 179.

The closing of the contactor bar 176 closes the circuit between the power lines 161 and 162 by way of the branch lines 172, 180 and 181, and the pressure switch 130. This maintains the energization of the operating coil 173 of the contactor switch 135 after the starting push button switch 134 has been released. The closing of the contactor bars 177 and 178 closes the circuit between the power lines 182 and 183 by way of 40 35 the windings of the valve-operating solenoid 133, energizing the latter and attracting its armature 151.

The solenoid 133, thus energized, pulls the valve rod 104 downward (Figure 1) so that the 45 valve heads 106 and 107 occupy their lower positions. When this occurs, the fluid pressure generated by the rams 46 through the action of the enlarged piston heads 47 in the cylinder bores 32 passes through the passageways 50 into the 50 space 33 above the auxiliary pressing plunger 49. The latter thus moves outward, and the fluid displaced thereby passes into the space beneath the piston heads 47 of the pressure-generating plungers 46. The fluid under pressure also backs 55 up in the plunger bores 85 and the pipe line 190, this being communicated to the pressure switch 130 by the branch line 191 (Figure 1). (Any additional fluid required by the press is supplied through the pipe line 190 and the check valve 160 from the tank 159.) When this pressure becomes great enough to overcome the force of the coil spring in the pressure switch 130, the latter opens, breaking the circuit energizing the valve-operating solenoid 133. The valve rod 104 60 and the valve heads 106 and 107 then move upward under the urge of the coil spring 152, the valve heads 106 and 107 coming to rest in the dotted positions (Figure 1). The fluid pressure within the auxiliary pressing plunger chamber 70 33 is immediately released, and no further pressure is placed upon the work-piece, as the fluid henceforth passes from the cylinders 32 through the plunger bores 85, the pipe line 190, the branch line 192, the piston valve 105, the branch line 75

193 and the exhaust line 194 back to the tank 159. This instant release of the pressure after a predetermined pressure has been reached is known as the "flash" pressure reversal as distinguished from the "dwell" pressure systems according to which the pressure is allowed to rise to a predetermined amount at which it remains until the press is reversed.

The platen 8 thus continues to move downward without applying pressure to the work-piece, and then passes upward on its return stroke. As it nears the limit of its upward motion, the end 147 of the arm 148 lifts the collar 145 and the rod 143, causing the collar 142 thereon to throw the limit switch 136. This action breaks the circuit, energizing the clutch-operating solenoid 131, causing it to release the clutch-operating rod 23. The clutch 19 accordingly opens, breaking the mechanical connection between the source of power and the main driving shaft 16 of the press. The platen 8, therefore, comes to rest at the upper limit of its stroke and recommences another working stroke only when the starting push button switch 134 is again depressed. When this occurs, the foregoing cycle of operation is repeated.

The operation of the press circuit shown in Figure 2 is electrically the same as that shown in Figure 1, but is hydraulically somewhat different. The starting push button switch 134 is depressed as before, and the solenoids 131 and 133 are similarly energized, causing the clutch 19 to be closed and the valve rod 104 to be pulled downward in the manner previously described. The same action causes the pump control rod 157 to be shifted through the motion of the bell-crank 154, causing pressure fluid to be discharged through the port 62 of the pump 64, the port 63 correspondingly becoming the suction port. The fluid pressure coming from the pump 64 by way of the pipe line 60 and the bore 59 in the plunger 57 passes into the cylinder bore 52 and thence into the space above the auxiliary pressing plunger 49, causing the latter to move outward and exert its pressure upon the work-piece. At the same time, the fluid displaced from beneath the pressing plunger 49 passes outward through the oblique passage 56 into the cylinder bore 52, and thence is drawn back to the pump 64 by way of the bore 59 in the plunger 58 and the pipe line 61 running to the suction port 63 of the pump 64. The differential valve 75 causes a constant supply of fluid to be available to the pump 64.

When the platen 8 and the auxiliary pressing plunger 49 of Figure 2 have exerted a sufficient pressure upon the work-piece to cause the pressure switch 130 to be thrown by the action of the fluid backing up in the pipe line 60 and the branch line 191, the solenoid 133 is deenergized in the same manner as previously described. The piston valve 105 then shifts, and its heads 106 and 107 move into their upper or dotted positions. Simultaneously with this, the pump control rod 157 moves inward through the action of the bellcrank 154, reversing the flow of fluid from the pump 64 and causing the port 63 to become the compression port and the port 62 the suction port. Fluid is then withdrawn from the cylinder 53 and the space above the auxiliary pressing plunger 49 by way of the pipe line 60, and the auxiliary pressing plunger 45 moves inward to release the pressure upon the work-piece. At the same time, pressure fluid is supplied to the under side of the auxiliary pressing plunger head 48 by

way of the pipe line 61 and the oblique passageway 56, thus accelerating the inward motion of the plunger 45. Throughout the remainder of the working stroke, therefore, substantially no pressure is exerted upon the work-piece. The platen 8 then reverses its motion, and trips the limit switch 136 at the upper limit of its motion, coming to rest in the manner previously described for Figure 1.

The operation of the press circuit shown in Figure 3 follows the electrical steps previously described for Figure 1. The energization of the solenoids 131 and 133 starts the platen 8 moving downward and exerts pressure upon the work-piece by the action of the auxiliary pressing plunger 49 as previously disclosed. The pump discharge passes by way of the pipe line 117 and the check valve 111 to the piston valve 105, thence along the pipe line 108 through the right-hand plunger 51 into the space above the auxiliary pressing plunger 49. The fluid displaced from beneath the latter is drawn outward through the oblique passageway 56, the plunger 58 and the pipe line 109, the piston valve 105, and the pipe line 113 to the tank 84. The pump 114 obtains liquid by way of its suction line 119 running to the tank 84. The high pressure regulating valve 112 at a predetermined pressure discharges fluid from the line 108 into the discharge line 113, leading back to the tank 84. The high pressure check valve 111 prevents a backward flow of fluid.

When the pressure exerted upon the work-piece by the auxiliary pressing plunger 49 reaches the pressure required to throw the pressure switch 130, the latter opens the circuit energizing the valve-operating solenoid 133. The heads 106 and 107 of the piston valve 105 then move upward (Figure 3), causing the pump discharge from the line 117 to be passed through the valve 105 into the line 109 leading to the space beneath the auxiliary pressing plunger 49 by way of the oblique passageway 56 and the plunger 58. The auxiliary pressing plunger 49 is rapidly forced inward under the action of this pressure, and the fluid on its opposite side escapes through the cylinder 53, the bore 59 in the plunger 57, the pipe lines 110 and 108, the valve 105 and the discharge line 113 to the tank 84. Thus the pressure upon the work-piece is instantly withdrawn when the predetermined pressure is reached, and the platen 8 continues downward for the remainder of its working stroke without exerting any substantial pressure upon the work-piece.

In the pressure switch 130 shown in Figure 3, a slight modification has been made over the pressure switches 130 previously described for Figures 1 and 2. The pressure switch 130 of Figure 3 is supplied with a side port 198, which communicates by way of the branch line 199 with the discharge line 113 leading to the tank 84. This causes the pressure switch 130 of Figure 3 to function also as a relief valve, and to discharge fluid when the pressure switch 130 is shifted.

In the foregoing cycle of operations described for Figures 1 to 4, inclusive, the platen has been caused to come to rest when it reaches the top of its return stroke, this action being obtained through the operation of the limit switch 136. In order to cause the press to repeat its stroke automatically without stopping at the upper limit of its return stroke, the normally-closed position-actuated switch 136 may be made non-effective by bridging it with the lines 200 and 201 containing the normally-open manually-operated switch

202 in parallel with the position switch 136 (Figure 4). When the switch 202 is closed, the clutch-operating contactor switch 132 and the solenoid 131 remain continuously energized, irrespective of the opening and closing of the position switch 136, causing the press platen 8 to make any desired number of working strokes in succession. When the switch 202 is opened, however, the position switch 136 again becomes operative to halt the platen 8 at the upper limit of its return stroke.

It will be observed that in the circuit of Figure 3, the variable delivery feature of the pump 114 is utilized as a means of pressure control only. It will be understood that I desire to comprehend within my invention such modifications as may be necessary to adapt it to varying conditions and uses.

Having thus fully described my invention, what I claim as new and desire to secure by Letters Patent is:

1. In combination in a press, a mechanically operable platen having associated therewith a cylinder, a ram reciprocably mounted in said cylinder, a fluid source adapted to supply fluid to said cylinder, mechanical means operable to advance said platen together with said ram while simultaneously causing said platen to create fluid pressure in said cylinder to additionally advance said ram, and means responsive to a predetermined pressure on said ram for releasing said last mentioned pressure and maintaining said ram substantially stationary while said platen continues its advancing stroke.

2. In combination in a press, a mechanically operable platen having associated therewith a main cylinder and an auxiliary cylinder, said cylinders being hydraulically connected with each other, a ram reciprocably mounted in said main cylinder, a plunger mounted in said auxiliary cylinder and permitting relative movement between said plunger and said auxiliary cylinder, a fluid source adapted to supply fluid to said cylinders, mechanical means operable to advance said platen together with said ram while simultaneously effecting relative movement of said plunger and said ram for creating fluid pressure in said main cylinder to additionally advance said ram, and means responsive to a predetermined pressure on said ram for releasing said last mentioned pressure and maintaining said ram substantially stationary while said platen continues its advancing stroke.

3. In combination in a press, a mechanically movable platen, mechanical means to move said platen through a predetermined working stroke, a hydraulically-operable ram associated with said platen and adapted to be advanced thereby, a fluid source for supplying fluid to said ram, means associated with said platen and responsive to the advancing movement thereof for exerting fluid pressure on said ram to additionally advance the same, and means responsive to the attainment of a predetermined pressure after the completion of a part of the working stroke for completely releasing pressure fluid on said ram while said ram continues its advancing stroke.

4. In combination in a press, a mechanically movable platen, mechanical means to move said platen through a predetermined working stroke, a hydraulically-operable ram associated with said platen and arranged for mechanical advancement by said platen, a fluid source for supplying fluid to said ram, means associated with said platen and responsive to the advancing

movement thereof for creating fluid pressure on said ram to additionally advance the same, a reversing valve for controlling the direction of flow of the fluid from said fluid source to said ram, and means responsive to the attainment of a predetermined pressure after the completion of a part of the working stroke for reversing said reversing valve while said platen continues its advancing stroke to completely release the pressure exerted by said ram upon the workpiece.

5. In combination in a press, a mechanically movable platen, mechanical means to move said platen through a predetermined working stroke, a hydraulically operable ram associated with said platen, and means for supplying fluid pressure to said ram to advance the same, means associated with said platen and responsive to the advancing movement for exerting additional fluid pressure on said ram to additionally advance said ram, and electrically actuated means responsive to the attainment of a predetermined pressure after the completion of a part of the working stroke for completely releasing the pressure on said ram while said platen continues its advancing stroke.

6. In combination in a press, a mechanically movable platen, mechanical means to move said platen through a predetermined working stroke, a hydraulically operable ram associated with said platen and adapted to be mechanically advanced by the movement of said platen, means for supplying pressure fluid to said ram for hydraulically advancing the same, said means including a

by-passing valve, means associated with said platen and responsive to the advancing movement thereof for exerting additional fluid pressure on said ram to additionally advance said ram, and electrically actuated means responsive to the attainment of a predetermined pressure after the completion of a part of the working stroke for reversing said by-passing valve to completely release the pressure exerted by said ram upon the workpiece while the advancing stroke of said platen continues, said pressure-supplying means including a reversible delivery pump with the reverse member thereof operatively connected to said by-passing valve.

7. In combination in a press, a mechanically movable platen, mechanical means to move said platen through a predetermined working stroke, a hydraulic circuit, a hydraulically operable ram connected with said circuit and reciprocally mounted upon said platen to travel therewith, said platen being movable to exert pressure on fluid from said circuit and to convey pressure fluid to said ram for additionally advancing the same, and means responsive to the attainment of a predetermined pressure in said circuit during the first portion of the advancing stroke of said platen for completely releasing the pressure on said ram and causing said platen to move substantially without exerting any substantial pressure upon the workpiece for the remainder of the advancing stroke of said platen.

HOWARD F. MACMILLIN.
